Primary Examiner — Shannon W Morgan*Assistant Examiner* — Terilyn Nicole Davis(74) *Attorney, Agent, or Firm* — Gloria Tsui-Yip; Gottlieb, Rackman & Reisman, P.C.(57) **CLAIM**

The ornamental design for a container for food, as shown and described.

DESCRIPTION

FIG. 1 is a front elevational view of a container for food showing my new design;

FIG. 2 is a top plan view thereof;

FIG. 3 is a rear elevational view thereof;

FIG. 4 is a bottom plan view thereof;

FIG. 5 is a left side elevational view thereof;

FIG. 6 is a right side elevational view thereof;

FIG. 7 is a top, left, and front perspective view thereof;

FIG. 8 is an exploded, perspective, view of FIG. 7 showing the container for food of my new design with additional internal components; and,

FIG. 9 is a different, exploded, perspective, view of FIG. 8 showing another view of the additional internal components. The broken lines in the drawings depict a fork and attachment that form no part of the claimed design.
